STRAPLESS BRA SINGER

Filed Oct. 15, 1947

FIG. 3

INVENTOR.
BY LOUIS SHULMAN
Edward H. Miller
ATTORNEY.

UNITED STATES PATENT OFFICE

2,472,765

STRAPLESS BRASSIÈRE

Louis Shulman, New York, N. Y.

Application October 15, 1947, Serial No. 779,964

1-Claim. (Cl. 2-42)

1

This invention relates to new and useful improvements in strapless brassières.

Heretofore, numerous types and designs of strapless brassières have been made which maintain their position without the need of shoulder straps. These strapless brassières usually make use of metallic wire forms or elastic portions inserted in various parts of the brassières. It is old to use elastic strips or tapes along portions of the top edge of brassières. However, such insertions were not sufficient to firmly and securely hold the brassières in place, and consequently additional supports, such as cross straps or inserts lower down on the brassières were used. The dominating feature of this invention resides in the arrangement of an elastic tape upon the top edge portion of a brassière in a manner so that it is capable of securely holding the strapless brassière in position without requiring additional supporting devices.

This invention particularly relates to a strapless brassière having two breast receiving pockets, a straight bottom edge portion, and a top edge portion which is low between said pockets and curved upwardly to the top portions of said pockets and then downwardly to the end portions of the brassière. This invention proposes an elastic tape mounted with elastic stitches along the entire length of said top edge portion of the brassière following the curvature thereof. It is proposed that this elastic tape when in a normally relaxed condition should contract the brassière into substantially U-shape form providing strapless holding up of the brassière when stretched straight and worn in a stretched condition.

Another object of the invention is the construction of a brassière as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front elevational view of a strapless brassière constructed in accordance with this invention and illustrated in a free condition.

Fig. 2 is a fragmentary front elevational view of the brassière shown in Fig. 1 but in a stretched out straight condition as it would appear when ready to be worn.

2

Fig. 3 is a fragmentary enlarged view of the top central portion of Fig. 2.

Fig. 4 is a vertical sectional view taken on the line 4—4 of Fig. 3.

This invention is applied to a brassière 10 of any design and construction provided it has two breast receiving pockets 11, a straight bottom edge portion 12, and a top edge portion 13 which is low at the point 14 between said pockets 11 and curved upwardly to the top portions 15 of said pockets and then downwardly to the end portions 16 and 17 of the brassière. The brassière 10 preferably is provided with stays 18 about the pockets 11 for supplementing the supporting action of the brassière. The end portions 16 and 17 are of conventional construction. The end portion 16 is provided with the usual elastic insert 21 and eyelets 19 cooperative with hooks 20 on the end portion 17 of the brassière. Further details of the brassière itself need not be given in this specification because they are not important in so far as this invention goes.

A new feature of the strapless brassière, in accordance with this invention, comprises an elastic tape 22 mounted with elastic stitches 23 along the entire length of said top edge portion 13 of the brassière, and in a normally relaxed position forming said brassière into substantially U-shape form, as clearly illustrated in Fig. 1, for providing strapless support of said brassière when stretched straight, as illustrated in Fig. 2, and worn in said stretched condition. The elastic tape 22 is in the form of a strip of elastic material which is bent along its longitudinal center 35 forming a top bent portion 24 and side portions 25 and 26. These side portions 25 and 26 engage on the front and back sides of the top edge portion of the brassière.

The elastic stitches 23 comprise conventional 40 zig-zag stitches well known in the art. The elastic tape 22 is mounted along the top edge portion 13 of the brassière by stretching it and sewing it down in a stretched condition. It is important that the elastic tape 22 have sufficient 45 elasticity and be stretched sufficiently when applied so that when it is free it is capable of forming the brassière into the U-shape formation illustrated in Fig. 1.

The operation and use of the new brassière 50 may be understood from the following:

The brassière, when in a free condition, appears as illustrated in Fig. 1. When worn the wearer merely grasps the two ends thereof and pulls them apart, stretching the brassière so that 55 it assumes the formation illustrated in Fig. 2,

and then engages the brassière in position about her body in the usual way. Because the elastic tape 22 extends the entire length of the top edge portion of the brassière it is capable of applying uniform pressure completely about the body of the wearer for securely and firmly holding the brassière in position without requiring the addition of cross straps, elastic inserts, or other devices.

From actual trial it was determined that short lengths of elastic tape mounted on portions of the top edge of the brassière did not suffice. Brassières so constructed were not secure. Moreover, it was also discovered that when the elastic tape 22 is mounted along the entire length of the top edge portion 13 of the brassière it does not materially deform the curvature of the top edge portion of the brassière when the latter is worn because of the reaction of the wearer's body against the brassière itself.

While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new and desire to secure by United States Letters Patent is:

5 In a strapless brassière, a sufficient length of elastic tape mounted across the top portion of the brassière in order to contract said top portion sufficiently when the brassière is in a free condition to give the brassière a U-shape in which the end portions of the brassière extend upwards of the central portion, and means for connecting said end portions when said brassière is stretched straight about a wearer's body and worn in order that the central portion of the brassière is forced upwards for lifting the breasts.

LOUIS SHULMAN.
